(57) **CLAIM**

The ornamental design for a conical embryo culture plate, as shown and described.

DESCRIPTION

FIG. 1, is an isometric view of the new conical embryo culture plate, showing the base and separable lid of my new design; FIG. 2, is a top view of the base thereof;

FIG. 3, is a side elevational view of the base thereof; FIG. 4, is a side elevational view of the base, rotated 90 degrees from the side elevational view of FIG. 3;

FIG. 5, is a top view of the lid thereof; FIG. 6, is a side elevational view of the lid thereof; and, FIG. 7, is a side elevational view of the lid, rotated 90 degrees from the side elevational view of FIG. 6.
